UNITED STATES PATENT OFFICE.

DANIEL DRAWBAUGH, OF EBERLY'S MILL, PENNSYLVANIA, ASSIGNOR TO
THE PEOPLE'S TELEPHONE COMPANY, OF NEW YORK.

TELEPHONE-TRANSMITTER.

SPECIFICATION forming part of Letters Patent No. 291,512, dated January 1, 1884.

Application filed March 24, 1883. (No model.)

To all whom it may concern:

Be it known that I, DANIEL DRAWBAUGH, of Eberly's Mill, Cumberland county, Pennsylvania, have invented a new and useful Improvement in Telephone-Transmitters, of which the following is a specification.

My invention relates to that class of telephone-transmitters in which a current is modified and rendered capable of transmitting articulate speech by passage through pieces of low conducting material in contact.

The invention consists in the construction of the instrument more particularly herein-after set forth, and in the devices described, whereby the carbons may be adjusted in more or less delicate contact.

In the accompanying drawings, Figure 1 is an elevation of the instrument with the back removed. Fig. 2 is a vertical section on the line *x x* of Fig. 1. Fig. 3 is a horizontal section on the line *y y* of Fig. 1.

Similar letters of reference indicate like parts.

A is the box or case of the instrument.

B is the outer cover, having a mouth-piece orifice, C, and D is the diaphragm. I have shown this diaphragm with a central perforation, E, covered by a piece of felt or similar material, F; but this construction is not at all essential, inasmuch as I may use a solid continuous diaphragm without such perforation or felt cover. I make said diaphragm preferably of wood or other non-conducting material, and to its rear side, and at about the center, I attach a metal bracket, G. To said bracket I pivot a metal cup, I. Within said cup is inserted a hollow cylinder of carbon or other non-conducting material, J. At the bottom of the cup, and within the hollow of said cylinder, I place a piece of rubber or other insulating material, L.

M is a cylinder, of carbon or other low conducting material, fitting loosely within the hollow cylinder I.

In the upper portion of cylinder M is rigidly secured a metal rod, N. The cup I is pivoted to the bracket G by means of a shaft, O, which is rigidly secured to the cup I, but passes loosely through the hole in the bracket G, and is prevented from coming out of said orifice

by the nut H. This shaft extends through the side of the case A, as shown in partial section, Fig. 1, and has at its outer end a lever, P. It will be obvious that when the cup I is caused to stand vertically the carbon cylinder N will rest upon the piece of insulating material L at the bottom of the hollow of the cylinder J; hence the contact between the carbon cylinder M and the cylinder J will be a very light one, and the instrument will then become a delicate microphone. When, however, the cup I is placed in an inclined position, as shown in Fig. 2, then a portion of the weight of the cylinder M will rest upon the inner side of the cylinder J, in which case the contact will be less delicate and the apparatus will be adapted for use as a speaking-telephone. It will be apparent that the delicacy of contact and initial pressure between the carbons will depend upon the inclination of the cup I; also, that said initial pressure will be less as the cup approaches a vertical position and greater as it more nearly approximates a horizontal position. A very convenient means is therefore afforded by this device of adjusting the telephone so that it shall be as sensitive as may be desired, this adjustment being effected by simply turning a lever, P, which is outside of the case of the instrument, and thus altering the inclination of the cup I.

The circuits in the instrument proceed as follows: from the battery to the binding-post 1, to the primary of the induction-coil Q, by the wire *a*, to the rod N, carbon M, carbon J, cup I, and bracket G, by the wire *b* to the spring R; thence to the plate S, binding post 2, and battery. The secondary wires *c d* of the induction-coil lead to the line binding-posts 3 and 4. From said wires branch wires *e f* lead to the binding-post 5 and 6, to which a receiving-instrument may be attached.

T is a hook or bracket to support a receiving-instrument, the ring of which, when in place, pushes up the projection U of the spring R, and so breaks circuit between the springs R and S.

I claim as my invention—

1. In a telephone-transmitter, the combination of two electrodes of low conducting material, one loose and the other annular in form,

attached to and upon a movable support and surrounding the first electrode, and means for varying the inclination of the second electrode and support, so that said second electrode may 5 sustain more or less of the weight of the first electrode, substantially as described.

2. In a telephone-transmitter, the combination of an electrode of low conducting material in the form of a hollow cylinder, vertically 10 disposed, having a piece of insulating material inserted in its lower end and sustained by a support, and a second electrode of low conducting material in the form of a solid cylinder, adapted to fit loosely in the first electrode 15 and to rest on said inserted piece of insulating material, and means for adjusting said first electrode and support at a desired inclination, so as to vary the proportion of weight of the second electrode respectively sustained by the 20 first electrode, substantially as described.

3. In a telephone-transmitter, the combination of a diaphragm, a hollow cylinder of low conducting material held in a support hinged

or pivoted to said diaphragm, a solid cylinder of low conducting material loosely fitting in 25 said hollow cylinder, and a means for turning said hollow cylinder on its pivot or hinge, substantially as described.

4. In a telephone-transmitter, a diaphragm of non-conducting material, a metal cup piv- 30 oted to said diaphragm, a hollow cylinder of low conducting material contained in said cup, a solid cylinder of low conducting material loosely fitting in said hollow cylinder, a piece 35 of insulating material arranged between the lower end of said solid cylinder and the cup, and means for turning said cup on its pivot or hinge, substantially as described.

5. In a telephone-transmitter, the combination of a diaphragm of non-conducting material, bracket G, cup I, carbon J, carbon M, 40 rod O, and lever P, substantially as described.

DANIEL DRAWBAUGH.
